[57] CLAIM

The ornamental design for a bottle, substantially as shown and described.

DESCRIPTION

FIG. 1 is an elevational view of a bottle showing my new design, the opposite side being substantially the same in appearance;

FIG. 2 is a top plan view;

FIG. 3 is a bottom plan view;

FIG. 4 is a view looking from the right of FIG. 1, the opposite side being substantially the same in appearance; and

FIG. 5 is a perspective view thereof.

FIG. 1.

FIG. 2.

FIG. 3.

FIG. 4.

FIG. 5.
